J. D. HILLIARD

FLUID BREAK SWITCH

Original Filed March 30, 1922

Inventor:
John D. Hilliard,
Alexander S. Lantz
His Attorney

Patented Dec. 25, 1928.

UNITED STATES PATENT OFFICE.

JOHN D. HILLIARD, OF SCHENECTADY, NEW YORK, ASSIGNOR TO GENERAL ELECTRIC COMPANY, A CORPORATION OF NEW YORK.

FLUID-BREAK SWITCH.

Original application filed March 30, 1922, Serial No. 548,155. Divided and this application filed July 1, 1925. Serial No. 40,937.

My invention relates to electric switches of the fluid break type and an object of my invention is to provide an improved switch of this character wherein the gas formed 5 within the switch is employed for causing a greater acceleration in the opening movement of the switch. Another object of my invention is the provision of means in the switch for decelerating the movable contact 10 after the arc is broken. This application is a division of my co-pending application, Serial No. 548,155, filed March 30, 1922.

My invention will be better understood from the following description taken in connection with the accompanying drawing, and 15 its scope will be pointed out in the appended claims.

The single figure of the drawing illustrates a side elevation of a switch involving my invention, parts being shown in section to more 20 clearly illustrate the construction.

Mounted upon the base 1 by means of the insulator 2 is the container 3 which is adapted to contain a suitable insulating liquid, 25 the level of which is indicated by the dotted line. At the bottom of the container 3 is the stationary contact 4 with which the movable contact 5 co-operates to control the circuit. The stationary contact 4 is electrically connected with the container 3 but the movable contact 5 is adapted to operate through an insulating bushing 6 supported at the top of the container. The container is formed 30 with a horizontal partition 7 extending across it and dividing the same into a lower and an upper chamber. The hollow cylindrical member 8 is carried centrally by the partition 7 and within this member moves the disk or enlargement 9 on the contact 5. The purpose of this construction is to 35 impart to the movable contact of the switch a very high velocity under the influence of the pressure created at the separation of the contacts. The function of the disk 9 is to offer a 40 large surface to the fluid under pressure so that the contact 5 will be moved with a greater force.

For decelerating the contact 5 I have provided a dash pot 10 submerged in the insulating liquid in the casing 3. This dash pot 45 as shown is mounted on the lower end of the insulator 6 and is adapted to receive the enlargement 9 after it has traversed the distance between the member 8 and the lower

end of the dash pot. It is obvious that this 55 dash pot may be embodied in a variety of forms. In the form illustrated I have shown it as a cup-shaped member having a central opening 11 which decreases somewhat in diameter from its lower end. I also have 60 provided openings 12 through the walls of the cup-shaped member to provide a passage for the liquid as the enlargement 9 moves in the dash pot. It will be noted that by reason of the taper of the opening 65 in the dash pot and by reason of the openings 12 in the walls thereof the resistance offered to the passage of the enlargement in the dash pot increases in proportion to the distance it has traversed from the lower end 70 thereof.

While I have described only one embodiment of my invention, I do not wish to be limited to the particular form shown and described as it will be apparent that modifications therein may be made without departing from the scope of my invention as set forth in the appended claims.

What I claim as new and desire to secure by Letters Patent of the United States, is,—

1. A switch comprising a casing adapted to contain insulating liquid, a fixed contact mounted at one end of the casing, a contact rod mounted to slide in the opposite end of the casing and having an enlarged intermediate portion, and a partition in the casing having a cylindrical opening for receiving the enlarged portion of the contact rod.

2. A switch comprising a casing adapted to contain insulating liquid, a fixed contact at one end thereof, a contact rod movable through the opposite end thereof, said rod having a piston like enlargement and spaced cylindrical members in said casing arranged successively to receive said enlargement during the open circuit movement of the contact rod whereby pressure on one side of the enlargement produced at the initial separation of the contacts accelerates the opening movement of the switch and pressure on the opposite side of the enlargement subsequently decelerates said movement.

3. A switch comprising a casing adapted to contain an insulating liquid, a fixed contact mounted at one end of the casing, a dash pot in the casing, a partition therein between the dash pot and the fixed contact having a central opening therein and a movable con-

tact rod having an enlarged portion forming a piston adapted when the switch is opened to pass through said opening and subsequently enter said dash pot.

5. 4. The combination with a receptacle adapted to contain a liquid, an insulator extending into said receptacle and formed with an opening therethrough, a dash pot supported by said insulator, a contact within 10 said receptacle, a second contact adapted to extend through the opening in said insulator into contact with said first-mentioned contact and withdrawable from said first-mentioned contact to break the circuit, said 15 second contact being formed with a surface arranged to be subject to the pressure within said liquid created by the arc formed at the separation of said contacts whereby a high velocity is imparted to said second contact, 20 said second contact being also provided with means adapted to cooperate with said dash pot, whereby said second contact may be subsequently decelerated.

5. The combination with a receptacle 25 adapted to contain a liquid, an insulator extending into said receptacle and formed with an opening therethrough, a dash pot supported by said insulator, a contact within 30 said receptacle, a second contact adapted to extend through the opening in said insulator into contact with said first-mentioned contact and withdrawable therefrom to break the circuit, said second contact being formed with a surface arranged to be subject to the

pressure within said liquid created by the 35 arc formed at the separation of said contacts whereby a high velocity is imparted to said second contact, said second contact being also provided with means adapted to cooperate with said dash pot whereby said latter 40 contact may be subsequently decelerated, and means within said receptacle for causing the liquid to be forced into the path of the arc during the separation of said contacts.

6. The combination with a receptacle 45 adapted to contain a liquid, an insulator extending into said receptacle and formed with an opening therethrough, a dash pot supported by said insulator, a contact within 50 said receptacle adapted to extend through the opening in said insulator into contact with said first-mentioned contact and separable from said first-mentioned contact to break the circuit, said latter contact being formed with a piston so arranged as to be 55 subject to the pressure within the liquid created by the arc formed at the separation of the contacts, and means within said receptacle for causing the said pressure to be exerted upon one side only of said piston whereby 60 said latter contact is forced away from said first-mentioned contact by the said pressure, said piston being arranged to cooperate with said dash pot subsequently to decelerate said contact.

In witness whereof, I have hereunto set my hand this 30th day of June, 1925.

JOHN D. HILLIARD.
